H. C. FOSTER

LAMP FOCUSING DEVICE

Filed April 5, 1926

FIG. 1

FIG. 2

INVENTOR.
HARRY C. FOSTER.

BY

Franklin L. Lusk
ATTORNEYS.

UNITED STATES PATENT OFFICE.

HARRY C. FOSTER, OF CONNERSVILLE, INDIANA, ASSIGNOR TO INDIANA LAMP CORPORATION, OF CONNERSVILLE, INDIANA, A CORPORATION.

LAMP-FOCUSING DEVICE.

Application filed April 5, 1926. Serial No. 39,843.

This invention pertains to a focusing device for headlamps, and particularly for adjusting the position of the bulb with respect to the reflector in automobile headlights.

The object of the invention is to provide an adjusting mechanism of simple construction wherein the bulb may be adjusted vertically through the medium of one externally actuated screw, or may be adjusted horizontally through the medium of a second externally actuated screw.

The full nature of the invention will be understood from the accompanying drawings and the following description and claims:

In the drawings, Figure 1 is a side elevation showing the device mounted in position with respect to the casing of the lamp. Fig. 2 is a section taken on the line 2—2 of Fig. 1.

In the drawings there is shown a lamp casing 10, a reflector 11, and a bulb 12 having a filament 13. The lamp bulb is supported by the usual bayonet slotted socket 14 extending freely through a suitable opening in the reflector 11. The socket 14 is provided with a pair of oppositely disposed rearwardly extending rounded ears 15 adapted to seat in corresponding rounded openings or recesses in a tubular extension socket 16, the adjacent ends of the sockets 14 and 16 being slightly spaced apart so as to allow a slight pivotal movement about the axis of the ears 15. The extension socket 16 is slidably mounted within the flanged opening 17 of the casing 10 and is adapted to receive a plug 18.

Rigidly secured to the extension socket 16 there is a collar 19 projecting upwardly to form a head 20 through which a screw 21 is adapted to extend, said screw 21 being provided with a cylindrical portion having the usual slot at one end projecting through the casing so as to permit ready access thereto by a screw driver. The other end of the cylindrical portion provides an end thrust bearing which engages the head 20, the shank or threaded portion of a screw extending therethrough and being surrounded by a spring 22. The bulb receiving socket 14 is likewise provided with a rigidly secured collar 23 having a head 24 through which the screw threaded shank portion of the screw 21 is adapted to screw. The inner

end of the screw is provided with a cotter pin for preventing its withdrawal from the collar 23, and the spring 22 is positioned intermediate the heads 20 and 24 of said collars.

Through the medium of the screw 21, the bulb may be tilted up or down, since upon rotation of said screw the head 24 of the collar 23 will be moved back and forth with respect to the rigid collar 19. Such movement of the collar 23 will actuate the socket 14 so as to tilt it about the center of curvature of the ears 15. This will permit of a focusing adjustment vertically.

Rigidly connected to the connecting socket 16 through the medium of a saddle 24, there is a flange member 25 through which a screw 26 is adapted to extend and engage the threads thereof. The end of the screw is split and spread so as to prevent it from being withdrawn. Said screw 26 freely extends through a suitable opening in the casing 10 so that its head is exposed for ready access of a screw driver or the like, and mounted about the shank portion of the screw intermediate said housing and the flange member 25 there is a spring 27.

Upon rotation of the screw 26 it will cause the flange 25 to move backwardly and forwardly with respect to the casing and therethrough impart a like movement to the connecting socket 16. Then said connecting socket, as well as the lamp socket 14 and the bulb 12, will be caused to move bodily back and forth for obtaining suitable horizontal adjustment.

The invention claimed is:

1. The combination with a lamp casing, a reflector, and a lamp bulb, of a focusing device including an extension socket slidably mounted in said casing, a bulb-receiving socket pivotally connected thereto, and independently actuated means for adjusting said bulb with respect to the reflector longitudinally of the sockets and substantially in a plane perpendicular thereto.

2. The combination with a lamp casing, a reflector, and a lamp bulb, of a focusing device including an extension socket slidably mounted in said casing, a bulb-receiving socket pivotally connected thereto, a screw having its head exposed through said casing for adjusting the bulb longitudinally of the sockets, and a second screw having

its head exposed through said casing for adjusting the bulb substantially in a plane perpendicular thereto.

3. The combination with a lamp casing, a reflector, and a lamp bulb, of a focusing device including an extension socket slidably mounted in said casing, a bulb-receiving socket pivotally connected to said extension socket and in alignment therewith, 10 means connected with said extension socket

for adjusting the bulb longitudinally thereof, and means connected with said bulb-receiving socket for adjusting the bulb substantially in a plane perpendicular thereto.

15 4. The combination with a lamp casing, and a reflector, of a focusing device having an extension socket slidably mounted in said casing, the forward end of said socket being provided with oppositely positioned 20 substantially circular openings in the sides thereof, a bulb-receiving socket extending through said reflector, a pair of substantially circular ears extending rearwardly therefrom so as to engage in said openings 25 and pivotally connect said sockets together, a bulb in said last-mentioned socket, means for causing both of said sockets to bodily move longitudinally thereof, and a second means for tilting said bulb about the center 30 of rotation of said ears.

5. The combination with a lamp casing, a reflector, and a lamp bulb, of a focusing device including an extension socket slidably mounted in said casing, a bulb-receiving 35 socket pivotally connected to said connecting socket and in alignment therewith, a screw member accessible for adjustment

from without the casing connected with one of said sockets for bodily moving them longitudinally for adjusting the bulb longitudinally thereof, and a second screw exposed externally of said casing in engagement with said bulb-receiving socket for tilting the same with respect to said extension socket and thereby adjusting said bulb substantially in a plane at right angles to 45 said sockets.

6. The combination with a lamp casing, a reflector, and a lamp bulb, of a focusing device having an extension socket slidably mounted in said casing, the forward end of 50 said socket being provided with oppositely positioned substantially circular openings in the sides thereof, a bulb-receiving socket extending through said reflector, a pair of 55 substantially circular ears extending rearwardly therefrom so as to engage in said openings and pivotally connect said sockets together, a bulb in said last-mentioned socket, a screw member accessible for adjustment from without the casing connected with one of said sockets for bodily moving them longitudinally for adjusting the bulb 60 longitudinally thereof, and a second screw exposed externally of said casing in engagement with said bulb-receiving socket for tilting the same with respect to said extension socket and thereby adjusting said bulb substantially in a plane at right angles to 65 said sockets.

In witness whereof, I have hereunto affixed my signature.

HARRY C. FOSTER.
